UNITED STATES PATENT OFFICE.

JOSEPH RAMON TORRES, OF NEW ORLEANS, LOUISIANA.

IMPROVEMENT IN REFRIGERATORS.

Specification forming part of Letters Patent No. 117,221, dated July 18, 1871.

To all whom it may concern:

Be it known that I, JOSEPH RAMON TORRES, of New Orleans, in the parish of Orleans and State of Louisiana, have invented a new and valuable Improvement in Refrigerators; and I do hereby declare that the following is a full, clear, and exact description of the construction and operation of the same, reference being had to the annexed drawing making a part of this specification, and to the letters and figures of reference marked thereon.

Figure 1 of the drawing is a representation of a front elevation of my invention. Fig. 2 is a vertical sectional view of the same.

My invention relates to refrigerators; and consists in a novel construction and arrangement of an apparatus intended to serve efficiently as a refrigerator and as a supply for a water-cooler.

In the accompanying drawing this refrigerator is shown as constructed with two interior apartments—B the upper and B' the lower apartment. C represents the refrigerator-case; D, a hinged lid to the apartment B; C', the floor or partition separating B from B'; D', vertical doors opening, by means of springs or hinges *i*, into the apartment B' at the front of the refrigerator; all constructed with double walls or made with interior spaces E, which are filled with charcoal.

F represents a zinc lining placed within the apartment B, and designed to contain ice for the purpose of keeping the apartment B' cool and supplying the detachable water-cooler G through the medium of a tube, G', which enters the lower part of the apartment B. H represents a strainer, formed in one of the corners of the zinc lining F, over the end of the tube G'. I represents small glass doors arranged within openings in the doors D, and working either on hinges or springs *i*. The water-cooler G is designed to be readily separated from the pipe G' in order that it may be easily cleaned.

I claim as my invention—

The refrigerator herein described, consisting of the case C, ice-chamber B having pipe G for connection with a separable water-cooler, inclined bottom strainer H, partition C', and preserving-chamber B', all combined and arranged substantially as specified.

In testimony that I claim the above I have hereunto subscribed my name in the presence of two witnesses.

JOSEPH RAMON TORRES.
